UNITED STATES PATENT OFFICE.

ELMER C. DITTMAR, OF WILLIAMSPORT, PENNSYLVANIA, ASSIGNEE TO THE CROMAR COMPANY, OF WILLIAMSPORT, PENNSYLVANIA, A CORPORATION OF PENNSYLVANIA.

BUFFER FOR MACHINES FOR FINISHING FLOORING.

Application filed September 14, 1921. Serial No. 500,657.

This invention relates to certain new and useful improvements in buffering or wiping devices especially adapted to be used in connection with an apparatus for applying 5 a heavier filler to a strip of lumber as disclosed in my application Serial No. 314,464, filed July 31, 1919, the object being to provide a buffering or wiping device so constructed that the wiping or buffering devices 10 can be readily inserted or removed in order to allow devices of various natures to be substituted for one another to meet the requirements in filling various kinds of wood.

Another and further object of the invention 15 is to provide a buffering or wiping device which is provided with a central cross of flexible material and a marginal portion of radially disposed wiping members which engage the face of the material having the 20 coating of filler in such a manner that the filler is wiped crosswise of the grain of the material so as to force the filler into the pores of the wood and to remove the surplus therefrom, said wiping members acting on 25 the material in such a manner as to give the same a polish as it passes the device.

Other and further objects and advantages 30 of the invention will be hereinafter set forth and the novel features thereof defined by the appended claims.

In the drawings,

Figure 1 is a top plan view of a portion 35 of an apparatus for filling strips of lumber showing the application of my improved construction of buffering or wiping devices;

Figure 2 is a horizontal section through the device;

Figure 3 is a face view showing some of 40 the wiping devices in position; and

Figure 4 is a similar view showing the device provided with a central cross of flexible strips and a marginal portion of brushes.

In the drawing 1 indicates the frame of 45 an apparatus, 2 a guide way through which the strip is adapted to be moved continuously and 3 is an adjustable carriage on which my improved construction or buffering or wiping device 4 is mounted so that it can be forced 50 into and out of contact with the face of the strip in its passage therethrough and held under the desired pressure.

My improved construction of wiping device comprises a hub member 5 which is

adapted to be revolvably mounted on the 55 carriage 3 in any suitable manner and driven in the direction opposite to the movement of the material, the particular construction of mounting and driving the wiper or buffer is immaterial and in the drawing 60 I have shown a belt for this purpose.

The hub 5 is provided with a disk portion 6 which is provided with a marginal flange 7 and an annular rib 8 spaced from the flange as clearly shown, said rib having a 65 plurality of radially arranged dove-tail shaped grooves 9 into which are adapted to be inserted wiping members 10 corresponding in shape to the groove, said members being inserted from the center and 70 forced outwardly against the marginal flange 7.

In Figure 3 the members 10 are formed of leather strips while in Figure 4 brushes 11 are substituted for the leather strips and it is, of course understood that these wiping devices can be formed of leather fabric, 75 rubber, wood or any other suitable material as I have found in practice that when operating on certain kinds of wood better results 80 can be obtained by using wiping devices with bristles, such as brushes, when operating on other kinds of wood rubber wiping devices, on other kinds of wood canvas wiping devices and on other kinds of wood rubber or wood 85 wiping devices are used and therefore I do not wish to limit myself to the use of any particular kind of wiping devices although I have found in practice that very good 90 results on ordinary oak wood can be obtained by forming a buffering or wiping device with a marginal portion formed of spaced brushes.

After the desired number of wiping devices have been inserted from the center into the dove-tail shaped grooves 9, segmental 95 members 12 are placed in the central portion of the disk, said members being of such a size as to leave spaces between the opposing edges of the segmental shaped members, between which wiping devices 13 are placed 100 so as to form a central cross, said device can be formed of fabric, rubber, wood or any other suitable material.

The curved edges of the segmental members 12 are formed beveled as shown at 14 105 and the inner ends of the wiping devices 10 are beveled as shown at 15 so as to engage these members and arranged opposite one or

more of the grooves 9 are threaded bores 16 in which are mounted screws 17 adapted to engage corresponding wiping member so as to force the same inwardly in order to hold the segmental members in position on the face of the disk and I have found by this construction that a wiping or rotating member can be formed in such a manner that various wiping devices or strips will be held securely in position on the face of the disk of the revolving member in such a manner that all danger of these members becoming detached when rotated at a high rate of speed is prevented and by this construction I am able to interchange the various wiping devices in order to substitute the kind of strip desired to operate on a particular kind of wood being treated very quickly. This also enables the worn out rubbing strip to be replaced by new ones by simply unscrewing a number of screws and removing the segments which allows the wiping devices to be forced inwardly and removed from their grooves.

It will also be seen that after the wiping devices have been inserted within the grooves formed in the rib of the disk that they are prevented from moving outwardly by the marginal flange and that when the segmental members are in position and the screws force one of the wiping devices against the outer edges of each segmental member, the wiping devices disposed between the segmental members are clamped between the same so that all of the members are held on the face of the disk securely.

What I claim is—

1. A buffing wheel for wood finishing machines comprising a hub having a disk provided with a marginal flange, the face of said hub being provided with an annular rib spaced from the flange provided with radial grooves, a series of wiping devices disposed in said grooves, segmental locking members disposed within said annular rib and adapted to engage said wiping devices, wiping devices arranged between the segments of said segmental members and means for engaging the outer wiping devices for forcing the same into engagement with the segmental members for holding said wiping devices in position.
2. A buffing wheel for wood finishing machines comprising a disk having a marginal flange on one face thereof, a rib formed on the face of said disk having grooves to receive wiping devices, said wiping devices being adapted to be inserted from the center and to engage the marginal flange and segmental members arranged within said rib having wiping devices disposed between the same.
3. A buffing wheel for wood finishing machines comprising a disk having a marginal flange on one face thereof, a rib formed on

the face of said disk provided with dovetail shaped grooves, brushes corresponding in shape to said grooves disposed therein, segmental members arranged on the face of said disk within said rib, leather wiping devices disposed between said segmental members and means carried by said disk for engaging said brushes for forcing said brushes towards the center for holding said segmental members in position on the face of said disk.

4. A buffing wheel for wood finishing machines having a marginal portion provided with radially disposed brushes and a central cross of strips of flexible material.

5. A device of the kind described comprising a disk having disposed on one face thereof a series of brushes and a central portion formed of strips of yielding material.

6. A buffing wheel for wood finishing machines comprising a disk having on one face thereof a marginal flange provided with threaded bores, an annular rib formed on the inner face of said disk and within said flange and spaced therefrom, said rib having dovetail shaped grooves, a series of wiping devices mounted within said grooves having beveled inner ends, segmental members disposed on the face of said disk having beveled edges engaging the beveled ends of said wiping devices, wiping devices disposed between said segmental members and screws mounted in said threaded bores for engaging one or more of said brushes for forcing said segmental members together, clamping said wiping devices in position on the face of said disk.

7. A buffer wheel for wood finishing machines comprising a disk having a marginal flange on one face thereof, a rib formed on the face of said disk having undercut grooves, wiping devices corresponding in shape to said grooves disposed in said grooves, segmental members arranged on the face of said disk within said rib having beveled outer faces and wiping devices slidably mounted in said grooves having beveled ends engaging the beveled faces of said segmental members and securing said segmental members on the face of said disk.

8. A buffer wheel comprising a disk having an annular enlargement provided with radial grooves, wiping devices interlocked in said grooves, segmental members arranged on the face of said disk within said enlargement, wiping devices disposed between said segmental members and means for forcing said first mentioned devices into engagement with said segmental members for clamping the last mentioned wiping devices between said segmental members.

In testimony whereof I hereunto affix my signature.

ELMER C. DITTMAR.
